UNITED STATES PATENT OFFICE.

JOHN G. CALLAN, OF BOSTON, MASSACHUSETTS, ASSIGNOR TO GENERAL ELECTRIC COMPANY, A CORPORATION OF NEW YORK.

GOVERNING LOW-PRESSURE TURBINES.

1,092,972.

Specification of Letters Patent. Patented Apr. 14, 1914.

Application filed December 4, 1912. Serial No. 734,860.

To all whom it may concern:

Be it known that I, JOHN G. CALLAN, a citizen of the United States, residing at Boston, county of Suffolk, State of Massachusetts, have invented certain new and useful Improvements in Governing Low-Pressure Turbines, of which the following is a specification.

This invention relates to elastic fluid turbines which are driven by low-pressure steam exhausted from high-pressure engines or from industrial apparatus. In the case where the turbine is carrying its own load, independent of the load on the high-pressure engine, it may frequently happen that the latter will drop, causing a decrease in the amount of exhaust steam furnished by said engine, and also a decrease in pressure in the receiver between engine and turbine, while the load requirements on the turbine may continue unchanged at full load. In this event, the turbine will drop a part of its load in spite of the efforts of its speed governor to prevent this by opening up the throttle valve in the low pressure main. This valve may open its widest and yet because of the failure of the supply the receiver pressure will not be sufficient to enable the turbine to carry its load.

My invention aims to overcome this difficulty by controlling the receiver pressure and by re-acting through said receiver on the valves of the high-pressure engine so that they will not be closed upon a drop in the load of said engine, but will continue to furnish sufficient steam to run the turbine. I accomplish this by closing successive nozzle valves on the turbine when the steam supply lessens and thereby keeping up or increasing the receiver pressure by lessening the aggregate nozzle area admitting steam to the turbine. As this receiver pressure increases, the engine, or engines, which exhaust into it will encounter correspondingly higher back-pressure, and will slow down whereupon its governor, or their governors, will in turn admit an increased supply of steam. This action will go on until equilibrium is again established with the new load division. Two things tend to re-establish this equilibrium; first, the increase of steam supply from the engine, or engines, determined by the increased back-pressure, and second, the increased energy per pound

of steam available for the turbine, determined by the same fact. With this arrangement, the total steam from the engine will always be used by the turbine and each will have the use of this steam through such pressure drop as is required to carry the exact load existing at any moment. The turbine governor will indirectly influence the engine governor to furnish such amount of steam as will do the combined work of the two units, and over a wide range between a predetermined maximum and a predetermined minimum turbine load no steam and no part of the available energy of the steam will be wasted. The method applies essentially to the types of turbines in which the number of nozzles in operation, or in general the steam area at entrance, can be varied by the action of the governor. This method may be combined with other governing methods in such manner as the circumstances indicate. In fact, I prefer to provide a by-pass around the turbine to the condenser, which will be opened when the minimum load on the turbine has been reached by opening all its admission nozzles, and yet a still further reduction is desired. Furthermore, the receiver or piping and separator between the engine and the turbine has a certain finite capacity, and may in addition contain some water of condensation which gives it a slight regenerator action. For this reason, when the nozzle valves are suddenly opened for the purpose of reducing the energy per pound of steam which is available to the turbine, there will be momentary reverse effect, due to the discharge of stored steam from the receiver, and the partial evaporation of any water which may have accumulated there. This would cause the turbine to show a momentary rise in speed and load, although the governor would be acting to reduce both these. Obviously this would cause a further opening of valves and consequently an unstable condition. For this reason, I prefer to arrange the by-pass around the turbine so that it is opened by any sudden opening movements of the valve gear and to add a vacuum-breaking device, which is preferably actuated whenever the governor acts so quickly to increase the area of steam entrance that even the opening of the by-pass is not sufficient. This vacuum breaker may

also be actuated to prevent runaway at zero load if required. In addition to all this, I may arrange means for admitting live steam at high pressure into the receiver on the quick closing of the turbine valves, thus promptly raising this pressure when necessary, and maintaining the speed on sudden load increase as on sudden load reduction; and in cases where the turbine is not a mixed-pressure machine, I prefer to arrange means for such admission of live steam to supply any temporary shortage due to extreme low load on the engines.

In the accompanying drawings, Figure 1 is an end elevation of a low-pressure turbine of the Curtis type, embodying my invention; Fig. 2 is a side elevation on a larger scale of the governing end of said turbine, partly in section, and Fig. 3 is a section on a still larger scale of the dash-pot which operates the by-pass.

The turbine shown is a horizontal machine receiving low-pressure steam through a main 1, and exhausting to a condenser 2 through the pipe 2. The main conveys the steam to a chamber 3 from which it is admitted by valves 4 to nozzles 5, 6, 7 and 8. A fifth nozzle 9 is permanently open. The nozzles 5 and 6 are actuated successively by a motor, preferably a hydraulic cylinder 10 controlled by a pilot valve 11. A similar motor 12, also controlled by said pilot valve, actuates the nozzles 7 and 8; the arrangement of the pilot valve and mechanism being such that the nozzles open in the order 5, 6, 7 and 8 and close in reverse order. A simple form of valve-operating mechanism is illustrated, comprising a bar 13 attached to the piston rod of the motor and containing cam slots 14, 15, one for each valve. On each valve stem 16 is a head 17 having a pin 18 engaging with its slots. The lower slot in each bar opens its valve before the upper slot acts and has an extension permitting a sufficient movement of the bar to open said upper valve without disturbing the already-open lower valve.

The pilot valve stem 19 is pivoted to a floating lever 20 linked to the arm 21 of the speed governor 22 and pivoted to an equalizing bar 23 which is pivoted to the two bars 13. Attached to this equalizer is the piston rod 24 of a valved piston 25, forming one element of a dash-pot whose cylinder or shell 26 is supported on a rod 27. A rock-arm 28 is pivoted to said rod and serves to actuate a throttle valve 29 in a by-pass 30 extending around the turbine from the main 1 to the pipe 2. A finger 31 on the spindle of the throttle valve, which is preferably of the butterfly type, is adapted to come in contact with the stem 32 of a vacuum-breaking valve in the by-pass on the condenser side of the throttle valve.

Leading into the main 1, preferably at an

elbow of the by-pass, is a pipe 33 connected directly with the boiler. A valve 34 controls said pipe, and can be opened by the rod 27 through suitable mechanism, such as a lever 35 linked to another lever 36 which is connected by a spring 37 with the rock-arm 28.

The operation is as follows: With minimum load on the turbine, the nozzle 9, which is always open, is supplemented by the nozzles 5, 6, 7, 8, which under these conditions are also open, both cam bars 13 being raised to their highest point. The amount of steam fed to the turbine is determined by some other source, which may be variable independently of the load on the turbine; such for example, as two or three engines working on independent loads and all exhausting into a common receiver from which the main 1 leads to the turbine. The problem is to take all the steam which the engines deliver, and get out of it just as much energy as the turbine load requires, while at the same time never imposing upon the engines any greater back-pressure in the receiver than is necessary. Under minimum load, with all the nozzle valves open, the amount of steam delivered to the turbine will pass through it and to the condenser with a relatively small drop of pressure. On the other hand, as the load on the turbine increases, the resulting drop in speed causes the speed governor 22 to lift the pilot valve 11 and start the motor 12, which pulls down its bar 13 and closes the valve 8, thus increasing the pressure drop through the turbine and consequently the energy derived by the turbine from a given amount of steam passing. As a consequence, the pressure in the receiver from which the turbine derives its supply will be increased, thus compelling the engines which exhaust into the receiver to operate under less favorable conditions and causing them to deliver a larger volume of steam. This adds to the other effect, since the turbine now not only derives more energy from each pound of steam which passes through it, but it also receives more steam. As further load is placed upon the turbine, the governor will close successively the valves of nozzles 7, 6 and 5. The receiver pressure will of course be progressively increased by this action, and when all the valves are closed and steam is admitted only at the nozzle 9, which is always open, the turbine is delivering the maximum load it can without resort to additional high pressure steam. Under these conditions the pressure in the receiver may be several pounds above atmosphere pressure.

If the turbine is not a mixed pressure machine, that is, has no valves to admit high pressure steam in case of an increase of load after all the nozzle valves are closed, then the valve 34 comes into play. By the

downward movement of the cam bars 13 the equalizer 23 is also depressed and forces the plunger 25 downwardly in the dash-pot 26 until it finally reaches the bottom of said shell. If now the governor causes the motors to depress the equalizer still further, the rod 27 will be forced down against the tension of the spring 37 whose upper end is held stationary by the arm 28. The rod 10 has a collar 38 engaging with the lever 36 which is thereby actuated and opens the valve 34. This admits boiler steam to the receiver and furnishes the turbine with additional energy to meet the additional load. 15 If it is desired to admit live steam to the receiver when the turbine valves are closed with unusual suddenness as explained in a preceding paragraph then the valve 39, Fig. 3, is omitted and the by-pass 40 constitutes 20 the only communication between the upper and lower end of the dash pot. Under these conditions a sudden downward motion of the equalizer 23 will act through the liquid in the dash-pot, which cannot instantly escape, to momentarily open the valve 34; but this valve will continually tend to close again under the influence of the spring 37 and the relatively slow flow of liquid through 25 40 will allow such closure soon after rapid downward motion of 23 ceases. If the valve 39 is provided as shown, then this temporary admission of live steam in response to sudden downward movement of equalizer 23 will not occur. Circumstances will determine 30 whether such a response is desirable or not. If the load on the low pressure turbine fluctuates violently and the receiver or piping furnishing its steam is of considerable capacity, then valve 39 should be permanently 35 closed, since under these conditions the action just explained will be highly desirable in maintaining regulation. Where reverse conditions obtain, valve 39 should be operative in order to minimize the amount of live and therefore expensive steam sent directly into the receiver. I prefer to so design valve 39 that it may be thrown out of operation or left in operation as the demands of the service require. 40 This may be accomplished by providing a set screw adapted to clamp the valve to its seat or to be backed off so that the valve is operative. Now on the other hand, assume a reduction in the load on the turbine. The 45 governor at once causes the motors 10 and 12 to open the valves 5, 6, 7, 8 in succession. The lifting of the bar 23 lifts the plunger 25, and the mass of liquid above said plunger communicates its movement to the shell 50 which rises with it, lifting the rod 27, shutting off the live steam valve 34, and opening the by-pass throttle 29. The dash pot has a controllable and adjustable by-pass 40 so that if the upward movement of the bar 23 55 is slow and gentle, the rod 27 may not be

raised at all, and certainly will not be raised very much, and will soon settle down to its normal position by reason of its weight and the pull of the spring 37. Such opening of the by-pass throttle 29 is therefore only 70 temporary, and has the effect of preventing the momentary rise in speed and load due to the action of water in the receiver as mentioned above; permitting the turbine to operate steadily at all times. Now assume that 75 the load on the turbine becomes so light that the opening of all the nozzle valves does not meet the conditions. The equalizer bar 23 will by this time have been lifted so far that the plunger 28 will strike the top of the 80 dash pot. Any further lifting of the bar by the action of the governor will cause a positive lift on the rod 27 and an opening of the throttle valve 29 in the by-pass 30. This, and the possible breaking of the vacuum also, will meet the situation supposed. 85

In accordance with the provisions of the patent statutes, I have described the principle of operation of my invention, together with the apparatus which I now consider to 90 represent the best embodiment thereof; but I desire to have it understood that the apparatus shown is only illustrative, and that the invention can be carried out by other means.

What I claim as new and desire to secure 95 by Letters Patent of the United States, is:—

1. The combination with a low pressure turbine connected to receive the exhaust from a high pressure engine, of a source of steam supply connected to said low pressure 100 turbine, a valve controlling said source, valve means for varying the area of admission to said low pressure turbine, a speed governor, and means controlled by said governor to first operate said valve means to decrease the effective area of admission upon a decrease of speed, and to then operate said valve to admit steam from said source to said low pressure turbine. 105

2. The combination with a low pressure 110 turbine connected to receive the exhaust from a high pressure engine, of valve means for varying the area of admission to said low pressure turbine, a normally closed by-pass around said turbine, a speed governor, and means controlled by said governor to first operate said valve means to increase the effective area of admission upon an increase of speed and to then open said by-pass. 115

3. The combination with a low-pressure turbine, of a connection for supplying steam thereto from the exhaust of a high pressure engine, valve means for varying the area of admission to said low pressure turbine, a 120 conduit joined to said connection for supplying steam thereto, a normally closed valve in said conduit, a speed governor, and means controlled by said governor to first operate said valve means to decrease the 125

effective area of admission upon an increase in load and to then open said valve to admit steam to said connection.

4. The combination with a low pressure turbine of a connection for supplying steam thereto from the exhaust of a high pressure engine, valve means for varying the area of admission to said low pressure turbine, a normally closed by-pass around said turbine, 10 a speed governor, means controlled by said governor to operate said valve means to increase the effective area of admission upon an increase of speed, and further means controlled by said governor to temporarily 15 open said by-pass upon a rapid operation of said valve means to increase the effective area of admission.

5. The combination with a low pressure turbine supplied with steam from a receiver connected with independently loaded engines, of a plurality of nozzle valves, a speed governor, and mechanism enabling said governor to close said valves in succession, as the speed drops, and vice versa.

25 6. The combination with a low pressure turbine supplied with steam from a receiver connected with independently loaded engines, of a plurality of nozzle valves, a speed governor, means whereby said governor will 30 close said valves in succession as the speed drops, and means enabling said governor to admit live steam to the receiver when all said nozzle valves have been closed.

7. The combination with a low pressure 35 turbine supplied with steam from a receiver connected with independently-loaded engines, of a plurality of nozzle valves, a speed governor, and means whereby said governor will successively open said valves as the load 40 on the turbine drops.

8. The combination with a low pressure turbine supplied with steam from a receiver connected with independently loaded engines, of a plurality of nozzle valves, a speed 45 governor, and means whereby said governor will successively open said valves as the load on the turbine drops, a by-pass around said

turbine, and means whereby said governor can open said by-pass when said nozzle valves have all been opened. 50

9. The combination with a low pressure turbine, of a plurality of nozzle valves, cam bars for operating them, motors for actuating said bars, a speed governor controlling said motors, a by-pass around said turbine, 55 a throttle valve in said by-pass, and a dash pot having one element moving with said bars, and the other connected to said throttle valve.

10. The combination with a low pressure 60 turbine supplied with steam from a receiver, of a plurality of nozzle valves, cam bars for operating said valves, motors for actuating said bars, a speed governor controlling said motors, a valve admitting live steam to said 65 receiver, and a dash pot having one element moving with said bars and the other operatively connected with said live steam valve.

11. The combination with a low pressure 70 turbine supplied with steam from a receiver, of two pairs of nozzle valves, a cam bar for successively operating the valves in each pair, a motor for each bar, a pilot valve common to both motors, a speed governor controlling said pilot valve, an equalizer 75 connecting the two cam bars, a by-pass around said turbine, a throttle valve in said by-pass, a valved dash pot plunger attached to said equalizer, a shell co-operating with said plunger, and a rod secured to said shell 80 and adapted to operate said throttle valve.

12. The combination with a low pressure turbine, supplied with steam from a receiver, of a permanently open nozzle, a plurality 85 of nozzles provided with valves, and a speed governor operating to close said valves upon an increase of load.

In witness whereof, I have hereunto set my hand this 30th day of November, 1912.
